SWITCH & SIGNAL COMPANY, OF SWISSVALE, PENNSYLVANIA, A CORPORATION OF
PENNSYLVANIA.

CONTACT-SPRING.

Specification of Letters Patent. Patented Apr. 16, 1918.

1,262,721.

Application filed August 27, 1914, Serial No. 858,942. Renewed July 13, 1916. Serial No. 109,031.

To all whom it may concern:

Be it known that I, HERBERT A. WALLACE, a citizen of the United States, residing at Pittsburgh, in the county of Allegheny and 5 State of Pennsylvania, have invented certain new and useful Improvements in Contact-Springs, of which the following is a specification.

My invention relates to contact springs.

10 One object of my invention is to provide a contact spring which is rigid in the plane of movement of the spring so that it can exert considerable contact pressure without bending, but which is easily distorted by 15 torsional stress so that the contacting edge of the spring can readily aline itself with the surface of the fixed contact block.

Another object of my invention is the construction of a contact spring of the above-20 described character from a single piece of material.

I will describe one form of contact spring embodying my invention, showing its application to a relay, and explain one method 25 of making the said spring, and will then point out the novel features thereof in claims.

In the accompanying drawings, Figure 1 is a view showing a portion of a relay having applied thereto one form of contact 30 spring embodying my invention. Fig. 2 is a top view on an enlarged scale showing the contact spring shown in Fig. 1. Fig. 3 is a bottom view on an enlarged scale showing the same contact spring and showing a 35 means for attaching it to the armature of the relay. Fig. 4 is a perspective view showing more clearly the construction of the contact spring shown in the preceding views. Fig. 5 is a plan and Fig. 6 a side 40 elevation of a blank from which the contact spring is formed.

Referring to Fig. 1, the relay here shown comprises an electromagnet 1 mounted on a top plate 2 and comprising a core 3 which 45 passes through the top plate 2 and to the lower end of which is secured a soft iron pole-piece 4. An armature 5 carrying two studs 7 of insulating material such as bone, is pivoted at point 6 and is adapted to be 50 attracted by the pole-piece 4 of the electromagnet when the latter is energized. As shown in Figs. 1 and 3, each stud is provided with a vertical saw cut through which passes a contact spring 8, which spring is 55 secured to the studs by means of pins 9

passing through holes 9^a in the spring (see Fig. 4). This spring carries two fingers 10 and 11 which are adapted to make contact with fixed contacts 12 or 13 according as the electromagnet 1 is energized or deener- 60 gized. The fixed contact 12 comprises as here shown a block of graphite mounted in a jaw formed in the head of a screw 17 which passes up through the plate 2 and is attached thereto by nuts 16. The fixed con- 65 tact 13 comprises a block of electro-conductive material fixed on a brass strip 18 which is attached to a screw 19, which screw is likewise mounted in top plate 2 by nuts 20. 70

The contact spring 8 and the fingers 10 and 11 attached thereto are preferably, though not necessarily, formed from a single piece of sheet metal, and may, for example, be made in the manner which I will now describe. I first punch from a piece of sheet 75 metal a blank of substantially the shape and proportions shown in Fig. 5, at the same time punching a tongue 11 as shown more clearly in Fig. 6 (in order to clearly illustrate the structure the thickness of the sheet 80 metal is greatly exaggerated in proportion to the other dimensions in Fig. 6). I then bend the tongue 11 on the line 11^b to the position shown in Figs. 1 and 4, so that its edge 11^a may make and break contact with the fixed 85 contact member 13 of Fig. 1. I then fold the right-hand part of the blank on the line 21, at the same time grasping the left-hand end as far as lines 10^b and bending it slightly upward to form the contact finger 90 10, the edge 10^a of which makes and breaks contact with the fixed contact member 12 of Fig. 1. The holes 9^a may then be formed in the folded portion of the spring to accommodate the pins 9 by which the spring 95 is attached to the relay armature.

Of course, if the back contact finger is not needed, as is sometimes the case, the tongue 11 would not be formed in punching the blank, but the operation would otherwise be 100 the same as I have just described.

It will be seen that the plane of the body of spring 8 is parallel to the direction of movement of the spring caused by relay armature 5, so that the spring resists bending 105 in this direction; considerable force can therefore be exerted on the spring by the relay armature, thus securing considerable pressure of the finger 10 on block 12 and thereby insuring good electrical contact be- 110.

tween these two members, without appreciable bending of the spring 8 in the vertical direction. The spring yields readily, however, to torsional stresses, so that it can 5 readily twist to aline the contacting edge 10^a against the contact block 12. Thus when armature 5 is attracted by pole-piece 4, if one end of edge 10^a strikes block 12, the finger 8 will readily twist, due to the force 10 exerted thereon by armature 5, and so will cause the entire length of edge 10^a to make contact with block 12.

Although I have shown and described only one form of contact spring embodying 15 my invention, it is understood that various changes and modifications may be made therein within the scope of the appended claims without departing from the spirit and scope of my invention.

20 Having thus described my invention, what I claim is:

1. The process of making a contact spring out of an elongated flat blank of sheet metal which consists in folding said blank longitudinally upward throughout one portion 25 and simultaneously bending the remaining flat portion of the blank upward.

2. The process of making a contact spring having an upper and a lower contact finger 30 out of an elongated flat blank of sheet metal which consists in cutting a tongue in said blank, bending said tongue downward to form one contact finger, then folding the blank longitudinally upward throughout 35 that portion of the blank which extends from one end of said blank to the root of said tongue and simultaneously bending the remaining flat portion of the blank upward to form the upper contact finger.

40 3. A contact spring formed out of a single strip of flexible material one portion of said strip being flat to form a straight contacting

edge, and another portion of said strip being folded lengthwise upon itself to form a lever portion.

45 4. A contact spring adapted for movement in one plane and comprising a single strip of flexible material, one portion of said strip being flat to form a straight contacting edge at right angles to said plane of movement, and another portion of said strip being folded longitudinally in said plane of movement to form a lever arm which yields readily to torsional strain but resists bending in the said plane of movement.

50 5. A contact spring formed out of a single strip of flexible material and comprising a lever arm portion wherein said strip is folded longitudinally upward, a lower contact finger formed of a tongue cut out of 55 said strip and bent downwardly from said lever arm portion; and an upper contact finger formed out of the remaining portion of said strip and bent upwardly from said lever arm.

60 6. A contact spring having a thin flat body portion capable of yielding readily under torsional stress, and a contacting edge the line of which is substantially perpendicular to the plane of said body portion.

65 7. A movable contact spring having a contacting edge the line of which is substantially perpendicular to the plane of movement, and a thin flat body portion lying in the plane of movement and capable of sufficient torsion to allow the contacting edge to aline itself against a flat surface.

70 In testimony whereof I affix my signature in presence of two witnesses,

HERBERT A. WALLACE.
